SIGNORS, BY MESNE ASSIGNMENTS, TO UNITED RESEARCH CORPORATION, OF LONG
ISLAND CITY, NEW YORK, A CORPORATION OF DELAWARE

SOUND-REPRODUCING APPARATUS

Application filed December 3, 1927. Serial No. 237,555.

Our invention relates to devices for converting electrical currents into sound vibrations and more particularly to couplings for connecting a plurality of loud speakers to a 5 thermionic amplifier.

One object of our invention is to provide a device for coupling an additional loud speaker to an amplifier which is coupled by a transformer to a loud speaker designed for 10 use with said amplifier.

Another object of our invention is to provide a device of the type mentioned which is of such nature that the connection to either of said loud speakers may be interrupted 15 without impairing the satisfactory operation of the other loud speaker.

A further object of our invention is to provide switch controlled devices for connecting a plurality of additional loud speakers 20 to an amplifier which is coupled by a transformer to a loud speaker designed for use with the amplifier, the switch controlled devices being operable to permit the separate or simultaneous use of the additional 25 loud speakers, or to open one or more circuits, and thereby render one or more of the additional loud speakers inoperative.

Other objects and advantages will appear as the description proceeds.

30 The accompanying drawing is a diagrammatic view of an apparatus embodying our invention.

1 designates the final electron tube of an amplifying device such as a radio receiving 35 set, the tube having the usual plate 2, a filament 3 and a grid 4, the connections of the filament grid not being shown as they are well known. From the plate 2, a conductor 5 extends to the primary coil 6 on a transformer 40 7, the secondary coil 8, of which is connected to a loud speaker 10, the connections including a switch 11.

The primary coil 6 is also connected to the positive terminal of a source of potential 12. 45 A conductor 13 extends from the negative terminal of the source of potential to an intermediate point on a conductor 14 which is connected at one end to a terminal of a loud speaker 15 and at the other end is in contact 50 with a switch 16 in the off position of the lat-

ter. The switch is connected by means of a conductor 17 to the other terminal of the loud speaker 15. A conductor 18 extends from the latter terminal to one terminal of a loud speaker 20 from the other terminal of 55 which a conductor 21 extends to a switch 22, and is in contact therewith when the latter is in the on position. A conductor 23 connects the switch 22 to the conductor 5 and has a condenser 24 included therein. 60

A conductor 25 extends from switch 22 from which it makes contact in the off position of the latter to the switch 16, with which it makes contact in the on position of the latter. 65

The switch 22 controls the operation of the loud speaker 20. When this switch is in its on position and the switch 16 is in off position, the current travels through the conductor 5, the conductor 23, including condenser 24, the switch 22 and the conductor 21, energizes the loud speaker 20, and continues through the conductors 18 and 17, the switch 16 and the conductors 14 and 13. Under 70 these conditions it will be apparent that the loud speaker 20 is operative while the loud speaker 15 is inoperative. 75

To operate the loud speaker 15 and render the loud speaker 20 inoperative, the switch 22 is moved to off position, and the switch 16 80 is moved to on position. The current then traverses conductors 5 and 23, the switch 22, the conductor 25, the switch 16 and the conductor 17; energizes the loud speaker 15 and continues through the conductors 14 and 13. 85

To operate loud speakers 15 and 20 simultaneously, both the switches 16 and 22 are moved to on position and the current then traverses conductors 5 and 23, switch 22, conductor 21, loud speaker 20, conductor 18, loud 90 speaker 15 and conductors 14 and 13.

When both of the switches 16 and 22 are in off positions, neither of the loud speakers 15 and 20 is operative, as will be obvious, and no current traverses conductor 23 or 13. 95

By means of the switch 11, the operation of the loud speaker 10 is controlled and it may be operated alone or simultaneously with either or both of the loud speakers 15 or 20.

In a model in which the invention has been 100

actually embodied, the loud speaker 10 was of the low impedance type, while the loud speakers 15 and 20 were of the high impedance type. The primary and secondary impedance of the output transformer were matched with the plate impedance and the impedance of the loud speaker 10. Because of the use of the condenser 24, currents of audio frequency are by-passed, but the satisfactory operation of the loud speaker 10 was not disturbed by the use or non-use of either or both of the loud speakers 15 and 20. By arranging the condenser 24 in series with both of loud speakers 15 and 20 the impedance of the load on the tube 1 was prevented from decreasing to a point that would impair the quality of reproduction in any of the loud speakers.

The importance of the invention will be apparent when it is considered that it makes possible the coupling of additional loud speakers to an amplifier coupled by a transformer to a reproducer which is designed for use with the amplifier, with no appreciable distortion regardless of which speaker or combination of speakers is functioning.

Our invention is not limited to the specific details of the constructions illustrated and described, but diverse modifications may be made within the spirit thereof. For instance, still other loud speakers may be added by employing the principles described. A substantial range of equivalents is contemplated within the scope of the appended claims.

35 What we claim and desire to protect by Letters Patent is:

1. The combination of a thermionic amplifier for amplifying audio frequency currents, a loud speaker, a transformer coupling said loud speaker to said amplifier and a second loud speaker connected to said amplifier at a point between said amplifier and said transformer.

2. The combination of a thermionic amplifier for amplifying audio frequency currents, a loud speaker, a transformer coupling said loud speaker to said amplifier, and a plurality of additional loud speakers connected to said amplifier at a point between said amplifier and said transformer.

3. The combination of a thermionic amplifier for amplifying audio frequency currents, a loud speaker, a transformer having a secondary coil connected to said loud speaker and a primary coil connected to said amplifier, and a condenser and a loud speaker connected in series with each other and connected to said amplifier in parallel with said primary coil.

60 4. The combination of a thermionic amplifier for amplifying audio frequency currents, a loud speaker, a transformer having a secondary coil connected to said loud speaker and a primary coil connected to said amplifier, a condenser and a plurality of addi-

tional loud speakers, said condenser and said additional loud speakers being connected in series with each other and connected to said amplifier in parallel with said primary coil.

5. The combination of a thermionic amplifier for amplifying audio frequency currents and having an out-put conductor, a loud speaker, a transformer having a secondary coil connected to said loud speaker, and a primary coil connected to said conductor, a source of potential connected in series with said primary coil, and a condenser and a second loud speaker connected in series with each other and in parallel with said primary coil and said source of potential.

6. The combination of a thermionic amplifier for amplifying audio frequency currents, a loud speaker, a transformer coupling said loud speaker to said amplifier, a second loud speaker connected to said amplifier at a point between said amplifier and said transformer coupling, and a switch in the connections for said second loud speaker which in open position renders said second loud speaker inoperative.

7. The combination of a thermionic amplifier for amplifying audio frequency currents, a loud speaker, a transformer having a secondary coil connected to said loud speaker and a primary coil connected to said amplifier, a plurality of additional loud speakers connected to said amplifier in series with each other and in parallel with said primary coil, and a switch in the connections of said plurality of loud speakers which in open position renders them inoperative.

8. The combination of a thermionic amplifier for amplifying audio frequency currents, a loud speaker, a transformer having a primary coil and a secondary coil, said primary coil being connected to said amplifier, a second loud speaker, and means for completing a circuit selectively either between said secondary coil and the first mentioned loud speaker, or between said second loud speaker and said amplifier, or simultaneously between said secondary coil and the said first mentioned loud speaker and between said second loud speaker and said amplifier.

9. The combination of a thermionic amplifier for amplifying audio frequency currents, a loud speaker, a transformer, including a secondary coil connected to said loud speaker and a primary coil connected to said amplifier, and a second loud speaker and a condenser connected to said amplifier in series with each other and in parallel with said primary coil.

10. The combination of a thermionic amplifier for amplifying audio frequency currents, a loud speaker, a transformer having a secondary coil connected to said loud speaker and a primary coil connected to said amplifier, and a second loud speaker and a condenser connected to said amplifier in series

- with each other and in parallel with said primary coil, and a switch in the connection for said condenser and said second loud speaker, which in open position renders said second loud speaker inoperative.
11. The combination of a thermionic amplifier for amplifying audio frequency currents, having an out-put conductor, a loud speaker, a transformer having a secondary coil connected to said loud speaker and a primary coil connected to said conductor, a source of potential connected in series with said primary coil, and a condenser, a second loud speaker, and a switch connected in series with each other and in parallel with said primary coil and said source of potential, said second loud speaker being inoperative when said switch is in open position.
12. The combination of a thermionic amplifier for amplifying audio frequency currents, a loud speaker, a transformer having a secondary coil connected to said loud speaker and a primary coil connected to said amplifier, a pair of additional loud speakers, a switch for each of said additional loud speakers, and means operable when either of said switches is in on position and the other is in off position for completing a circuit from said amplifier through the loud speaker corresponding to the switch in on position, said other additional loud speaker remaining inoperative.
13. The combination of a thermionic amplifier for amplifying audio frequency currents, a loud speaker, a transformer having a secondary coil connected to said loud speaker and a primary coil connected to said amplifier, a pair of additional loud speakers, a switch for each of said additional loud speakers, and means operable when one of said switches is in on position, and the other is in off position for completing a circuit from said amplifier through the loud speaker corresponding to the switch in on position, said other additional loud speaker remaining inoperative, both of said switches being movable to off position to render said additional loud speakers simultaneously inoperative.
14. In an electric circuit, the combination with a plurality of electro-responsive devices, of means for effecting energization of said devices either selectively or simultaneously, comprising a plurality of single-pole, double-throw switches, one of said switches being arranged to connect one side of the circuit either to one terminal of one of said devices or to one terminal of another of said switches, and said other of said switches being arranged to connect the other terminal of said one of said devices and one terminal of another of said devices either to said one terminal of said other switch or to the other terminal of said other of said devices.
15. In an electric circuit, the combination with two electro-responsive devices having a common terminal and each having an opposite individual terminal, of means for effecting energization of said devices either selectively or simultaneously, comprising two single-pole, double-throw switches, one of said switches being arranged to connect one side of the circuit either to the individual terminal of one of said devices or to one terminal of the other of said switches, and the latter switch being arranged to connect said common terminal of said devices either to said one terminal of said latter switch or to the individual terminal of the other of said devices.
16. In an electric circuit, the combination with two electro-responsive devices having a common terminal and each having an opposite individual terminal, of means for effecting energization of said devices either selectively or simultaneously, comprising two switches each having a contacting member and two terminals adapted to be contacted selectively by said contacting member, a connection from one side of the circuit to the contacting member of one of said switches, a connection from one terminal of said one of the switches to the individual terminal of one of said devices, a connection from the other terminal of said one of said switches to one terminal of the other of said switches, a connection from the common terminal of said devices to the contacting member of said other of the switches, and connections from the other terminal of said other of said switches to the individual terminal of the other of said devices and to the other side of the circuit.
